UNITED STATES PATENT OFFICE.

FREDERICK W. WOLFF, OF CRESTON, IOWA.

WINDMILL.

SPECIFICATION forming part of Letters Patent No. 250,470, dated December 6, 1881.

Application filed October 18, 1881. (No model.)

To all whom it may concern:

Be it known that I, FREDERICK W. WOLFF, a citizen of the United States, residing at Creston, in the county of Union and State of Iowa, have invented certain new and useful Improvements in Windmills, of which the following is a specification, reference being had therein to the accompanying drawing.

This invention relates to windmills, and the object of the invention is to furnish means of transmitting the power furnished by the wind-wheel to distances, past intervening buildings, around hills and other intervening objects, in order that the windmill may be set in the most desirable and favorable place for operating a pump or other device where it is required to have it located.

The accompanying drawing is a perspective illustrating my invention.

Referring to the drawing by letters, letter A represents the tower, B the wind-wheel crank-shaft, and C the connecting-rod of an ordinary windmill, the wind-wheel not being shown.

D is a bell-crank, journaled at its bend on a shaft, d, which is secured to the tower A, so as to oscillate in a vertical plane, and has its horizontal arm or end hinged or journaled to the connecting-rod C, and its vertical end or arm hinged or journaled to a connecting-rod, E, which extends to and is connected at its other end to a bell-crank, F, which is arranged to oscillate in a horizontal plane, and is journaled at its bend to a post or any suitable fixed object, G. The other end of the bell-crank F is hinged or journaled to a connecting-rod, H, which extends and is journaled to one end of a bell-crank, I, which is arranged to oscillate in a vertical plane, and is journaled at its bend to a post, J. The other end of the bell-crank I is journaled to the connecting-rod K of the pump L.

M is a barn or other building, intervening between the windmill and pump L; and it will be seen that by means of the bell-crank levers arranged to oscillate, part of them in horizontal, and part of them in vertical, planes, I am enabled to transmit the force derived from the wheel past this barn or intervening object.

It will be obvious that by lengthening the connecting-rods and increasing their number and angular relations to each other the extent to which the force of the wind-wheel in passing intervening objects may be increased greatly exceeds what I have shown.

By means of my invention the farmer may locate his windmill in the most desirable locality, and then transmit the force derived from it, past intervening objects, to wherever he desires to use it.

Having thus described my invention, what I claim as new is—

1. In combination with a windmill and connecting-rods, bell-cranks, part of which are arranged to oscillate in vertical and part in horizontal planes, whereby the force derived from the wind-wheel may be transmitted past intervening objects, substantially as and for the purposes specified.

2. In combination with a windmill, the bell-cranks D and I, arranged to oscillate in vertical planes, the bell-crank F, arranged to oscillate in a horizontal plane, and the connecting-rods E and H, substantially as and for the purpose specified.

In testimony whereof I affix my signature in presence of two witnesses.

FREDERICK W. WOLFF.
